UNITED STATES PATENT OFFICE

FRANK SLUSHER, OF AKRON, OHIO, ASSIGNOR TO THE B. F. GOODRICH COMPANY, OF NEW YORK, N. Y., A CORPORATION OF NEW YORK

WRAPPING METHOD AND APPARATUS

Application filed April 21, 1927. Serial No. 185,481.

This invention relates to methods and apparatus for applying a wrapping of strand material to an article and is especially directed to wrapping rubberized tape upon a tire-bead core of the wound type to anchor the ends of the winding to the body of the tire-bead core.

My chief objects are to provide for economy of labor and material, and to provide uniformity and a desirably smooth and tight wrapping of the tape in successive bead-cores. More specific objects are to provide a largely automatic machine for this type of work and to provide for simplicity and efficiency in such a machine. A further specific object is to provide for wrapping the article without carrying a supply-spool of the tape or other strand material about the article being wrapped. Further and more detailed objects will be manifest.

Of the accompanying drawings,

Fig. 1 is a front elevation of a machine embodying and adapted to carry out my invention in its preferred form.

Fig. 2 is a side elevation of the same, from the right of Fig. 1, with parts broken away.

Fig. 3 is a section on line 3—3 of Fig. 1, one of the fabric-feeding slides being sectioned in a different plane.

Fig. 4 is an elevation, from the right of Fig. 1, of the left-hand winder assembly of the machine as viewed in Fig. 1.

Fig. 5 is a sectional view of parts of the machine, including the right-hand winder device of Fig. 1.

Fig. 6 is an elevation of a clutch mechanism as viewed from the rear of the machine.

Fig. 7 is an elevation, from the right of Fig. 1, of the driving means and the starting and stopping means, and a work receiving member.

Fig. 8 is a fragmentary elevation of the finished work.

General description

The machine in its preferred form comprises a pair of ring winders axially spaced apart at such distance from each other as to operate at the same time to wrap down the two ends respectively of the wire wind-

ing of a bead core in which end portions of the wire winding overlap each other in the circumference of the bead core, requiring wrappings of tape at a considerable distance from each other upon the annular bead core.

Instrumentalities are provided for drawing the bead core into the two ring winders and clamping it therein, for adhesively attaching the leading ends of respective tapes to the portions of the bead core which are to be wrapped, for cutting off suitable lengths of the tapes before the winding is started, for driving the ring winders to effect the winding or wrapping of the lengths of tape upon the bead core, and for ejecting the finished product from the winders.

Detailed description

Referring to the drawings, the machine as here shown comprises a frame 10 from which rises a pair of multiple-bearing brackets 11, 12 upon which are mounted respective ring winders 13, 14, upon the inner faces of the brackets, the winders being swiveled upon respective hollow, radially slotted stub shafts 13^a, 14^a, (Figs. 3, 4 and 5), so that non-rotating work-manipulating devices may be mounted upon and adjacent their faces which are the nearer to the middle of the machine.

In general, with a few exceptions, odd numerals are used herein for parts at the left-hand side of the machine and even numerals for parts at the right-hand side.

Each of the winders is formed with a radial, work-receiving slot, 15 or 16, the slot being registrable with the radial slot, 17 or 18, formed in the winder's shaft and each winder is formed on its periphery with a set of gear teeth 19 or 20 which are meshed with two idler pinions 21, 23 or 22, 24, the duplication of pinions assuring proper drive notwithstanding the radial slot in the winder. The pinions 21 and 22 are secured upon a shaft 25 and the pinions 23 and 24 upon a shaft 26, and the pinions 22, 24 of the right-hand winder 14 are meshed with a gear 27 which is loosely journaled upon a shaft 28 and is provided with a hub pinion 29 adapted to be intermittently driven by a mu-

tilated gear 30 which is secured upon the main drive shaft 31 of the machine, upon the inner side of the bearing bracket 12.

Secured upon the drive shaft 31 outside of the bracket 12 is a large driving gear 32 meshed with a pinion 33 secured upon a hollow shaft 34^a mounted in a bearing formed in the bracket 12, the said hollow shaft 34^a having secured thereon at the other side of the bracket a jaw-clutch member 33^a (Fig. 6) formed with a brake surface 33^b and adapted to mate with a clutch member 213 which is splined upon a shaft 34 journaled in the hollow shaft 34^a and having driving connection, through a sprocket 35, sprocket chain 36 and reduction gear 37, with a motor 38.

For engaging a tire bead core 39 and drawing it into the winders the machine is provided at the inner side of each winder with a hook, 41 or 42, formed upon the projecting end of a slide 43 or 44, (see the slide 43, Fig. 3), the slide being formed with guide-receiving slots or openings and mounted upon guide blocks such as the blocks 45, 47 mounted upon the shafts 25 and 31. The hooks 41 and 42, as will be seen upon reference to the hook 41, Fig. 3, are adapted to receive the bead core 39 from below when the hooks are in projected positions outside of the peripheries of the respective winders, and upon retraction of the slides are adapted to draw the bead core to the axis of the winders, through the radial slots of the latter, as shown in Fig. 3, and to clamp the bead core against the end walls of the slots in the winders' shafts (see Fig. 5).

Acting at the outer side of each of the winders to assist in drawing the bead core 40 into wrapping position and to eject the core from the winders after it is wrapped, a slide 47^a or 48 (see the slide 48, Fig. 2), generally similar to the slide 43 of Fig. 3, is mounted upon guide blocks, such as the blocks 50, 52 in Fig. 2, which are mounted upon the shafts 25 and 31 respectively. Each of these slides is formed near its forward end with a downwardly extending projection, 53 or 54, adapted to eject the bead core 39 from the winders in the forward movement of the slide, and pivoted to the forward end of the slide as at 56 (see Fig. 2) is a sector-shaped plate, 57 or 58, formed with a peripheral notch such as the notch 60 (Fig. 2), adapted 45 to receive the bead core 39 from below when the plate is in its lowermost position, as shown in broken lines in Fig. 2, where the plate is stopped by a stud, 61 or 62, mounted thereon and abutting the upper edge of the slide upon which the plate is mounted, the plate 57 or 58 being adapted to be turned about its pivot by upward forcing of the bead core in the slot 60 to a position such that the bead core is confined within the 50 notch by the ejector projection, 53 or 54, of

the slide, as shown in full lines in Fig. 2. The plate is provided with a rounded detent such as the detent 64 (Fig. 2) adapted to be engaged in a dimple formed in a stud such as the stud 66 mounted on the end of a spring clip such as the clip 68 which is secured to the outer face of the slide 48 with the stud 66 projecting through an aperture in the slide, the stud 66 and the spring clip 68 thus being adapted to retain the plate 57 or 58 in work-retaining position against the weight of the core 39, but to be disengaged from each other in the forward, work-ejecting movement of the slide by a pawl-like trip member 69 or 70 pivoted at 71 or 72 on a projecting part 73 or 74 of the bracket 11 or 12. The pawl-like member is formed with stop, 75 or 76, adapted to abut the upper edge of its mounting to cause the pawl to force the work-holding plate 57 or 58 downward as the plate passes the periphery of the winder, to drop the bead core 39, the pawl being adapted to swing freely in the opposite direction to permit the passage of the work-holding plate in work-retaining position toward the axis of the winder.

For actuating the two pairs of slides 43, 44 and 47, 48 in timed relation to the successive operations of the winders, the said slides are connected by respective links 77, 78, 79, 80 (see Fig. 1) with arms 81, 82, 83, 84 secured upon a rock shaft 85 having secured upon one end thereof a rocker arm 86 connected by an adjustable link 88 with one arm of a bell crank lever 90 loosely journaled upon a shaft 91 and having upon its other arm a cam-roller 92 running in a cam slot 94 formed in the face of the main drive gear 32 of the machine. (See Fig. 2.)

For presenting the ends of respective binding tapes 95, 96 at the winders' axis in position to be stuck to the bead core 39 upon the arrival of the latter, respective slides 97, 98 are mounted for vertical reciprocation upon respective guide members 99, 100 projecting from the brackets 11 and 12, each slide being formed with a guide-way for the tape and provided with a pawl 101 and 102 urged against the tape by a pull spring 103 or 104, the pawl being adapted to compel the tape to descend with the slide but to permit the tape to remain stationary while the slide runs upward thereon.

For vertically reciprocating the slides 97, 98 in timed relation to the successive operations of the winders each slide is formed at the rear with ears connected by a pin 105 or 106 mounted in the forked end of an arm 107 or 108, the said arms being secured against relative rotation upon a rock shaft 109 provided with a rocker arm 110 having a cam roller 111 running in a cam groove 112 formed in the face of a cam disk 113 secured upon the main drive shaft 31.

For feeding the tapes 95, 96 in response to

the downward pull of the tapes by the pawls 101, 102 the main drive gear 32 is meshed with an idler pinion 114 which drives a gear 115 secured upon a shaft 116 provided with feed drums 117, 118 for the respective tapes, the tapes being drawn from supply reels such as the reel 119 (Fig. 2) and so guided about guide pulleys 121, 123 (Fig. 3) or 122, 124 (Fig. 2) as to contact a large part of the 10 surface of the constantly driven feed drum 117 or 118, the said drum slipping within the loop of tape when the tension upon the latter is light, but driving the tape forward when the tape is so tensioned by movement of the 15 vertically-moving, tape-drawing slide as to cause the loop frictionally to grip the said drum.

To prevent excessively sudden increases of tension in the tapes the machine is provided 20 adjacent each tape-drawing slide with a floating tension roller 125 or 126 journaled upon the end of an arm 127 or 128 secured upon a shaft 129 or 130 journaled in an extension of the bearing bracket 11 or 12, the tension roller 25 being limited to downward movement by a stop 131 or 132 projecting from the rear end of the mounting-arm of the roller. The shaft 129 or 130 is provided with an arm such as the arm 134 (Fig. 2) connected by a pull 30 spring 136 with a stationary part of the framing, to urge the floating tension roller downward in a loop of the tape, between guide rollers 137, 139 or 138, 140 over which the tape passes to the tape-drawing slide.

35 For sticking the positioned leading end of the tape to the bead core 39 a pair of rollers such as the rollers 141, 143 (Figs. 3 and 4) are journaled in rocking frames such as the frames 145, 147, which are pivoted respectively as at 149, 151 upon one arm of a two arm cam lever such as the lever 153, which is fulcrumed at 155 upon the inner face of the winder 13 and adapted to urge the rocking frames and their rollers 141, 143 toward the 45 axis of the winder under the force of a pull spring 157 connecting with a part of the winder 13 the arm of the lever 153 upon which the rocking frames 145, 147 are mounted. The said rollers' frames are connected by a 50 pull spring such as the spring 159 to hold the rollers against each other when they are retracted from the work and to permit them to spread apart upon the work as they are pressed thereagainst, to roll and press the 55 tape against the bead core 39 in opposite directions from one corner thereof, as shown in Fig. 3. A stop 161 is provided upon the face of the winder to limit the movement of the adjacent arm of the lever 153 toward the 60 winder axis when the winder is empty and stops 163, 165 are provided upon the said arm and adapted to engage rearward projections of the rocking frames 145, 147, beyond their pivots, to assure proper positioning of the 65 rollers 141, 143 when they are in a retracted

position and also during their movement toward the work.

For withdrawing the rollers, 141, 143, from the work at the end of each wrapping operation and for holding them retracted while the winder is stopped, the actuating arm of the lever 153 is provided with a cam roller 167 adapted to coact with a cam arm 169 when the latter is presented in the path of the roller. The cam arm 169 is slidably 70 keyed upon the shaft 28, a generally similar cam arm 170, formed to clear the hub pinion 29 of the gear 27, being secured on the shaft 28 for actuation of the tape rolling devices of the other winder, and the shaft 28 is provided with a rocker arm 171 (Figs. 1 and 3) having at its outer end a cam roller 172 running in a cam groove 173 formed in a cam disk 174 secured upon the main drive shaft 31, the said cam disk being adapted to cause 75 the cam arms 169, 170 to be lifted into position to coact with the rollers, such as the roller 167, of the tape rolling devices, at the end of each operation of the winders, to retract the rollers such as the rollers 141, 143 80 from the work and hold them in retracted position until the tape ends have been fed into position to be stuck to the next bead core and until the bead core has arrived at the winding 85 position.

For assuring the proper stopping and holding of the winders in work-receiving position, with their radial work-receiving slots in registry with the slots formed in their shafts, a ratchet disk 175 is rotatably mounted 90 upon the shaft 28 and secured to the gear 27, the disk being formed with a peripheral notch 176 (Figs. 2 and 5) adapted to receive a stop pawl 177 which is rotatably mounted upon a stub shaft 178 projecting from the bracket 12, the said pawl having its hub interlocked with a cam arm 179 rotatably mounted upon the shaft 178 and having its outer end held by a pull spring 180 against a cam 181 secured upon the hub of the mutilated gear 30, the cam 181 being adapted to retract the pawl 177 from the disk 175 just before the mutilated gear 30 meshes with the pinion 29, and to permit the spring 180 to move the pawl 177 into contact with the disk 110 175 to engage in the notch 176 as the mutilated gear 30 passes out of mesh with the pinion 29.

For severing appropriate lengths from the leading end portions of the tapes 95, 96 after 115 the rollers such as the rollers 141, 143 have attached the leading ends of the tapes to the bead core, and for gripping the severed lengths of tape with sufficient force to cause them to be drawn onto the core with suitable tension, each winder is formed with a pair of guide ways, 183, 183 (Fig. 3) or 184, 184 (Fig. 5), for a pair of slides, 185, 187 (Fig. 3) or 186, 188 (Fig. 5), which are connected 120 on the outer side of the winder by a pair of 125 130

toggle links 189, 191 or 190, 192, and by a pull spring 193 or 194 adapted during rotation of the winder to hold the slides together with their toggle in broken position.

5 On the inner side of the winder the slides are provided on their upper faces with shear plates such as the plates 195, 197 (Figs. 3 and 4) adapted to sever the tape as the slides are brought together upon the latter, and the 10 slides are provided with downwardly extending grippers such as the grippers 199, 201 adapted to grip the severed length of the tape as shown in Fig. 3, under the force of the spring 193 or 194, to cause the winder to pull 15 the tape onto the bead core with appropriate tension, the tape gradually slipping from the said grippers as the winder rotates.

For straightening the toggle at the times when the winders are stopped in work-receiving position, to separate the slides and admit the next length of tape, and then to break the toggle and permit the slides to be drawn together by the spring to sever and grip the tape, an arm, 203 or 204, is secured upon 25 the shaft 91 and formed at its outer end with a laterally facing slot disposed tangentially of the winder and adapted to receive a stud, 207 or 208, mounted upon the hinge pin by which the slide actuating toggle links are 30 connected with each other, the slot being adapted to be occupied by the said stud when the winder is stopped in work-receiving position.

For appropriately lowering and raising the 35 arms 203 and 204 the shaft 91 is provided with a rocker arm 210 having at its outer end a cam roller 211 (Fig. 5) running in a cam groove 212 formed in the rear face of the mutilated gear 30.

40 For cyclic operation of the machine in successive wrapping operations the jaw-clutch member 213, splined on the shaft 34 and adapted to mate with the jaw-clutch member 33^a, is circumferentially grooved and engaged by a shipper fork 214 (Fig. 6) formed on the upper arm of a three-armed lever 215 secured upon a shaft 216 which extends to the front of the machine, the lowermost arm 217 of the lever 215 being connected with a part 45 of the machine frame by a pull spring 218 adapted to urge the clutch member 213 toward disengaged position.

For latching the clutch member 213 in engagement with the clutch member 33^a the 50 lever 215 has a middle arm 219 adapted to be engaged by a shoulder formed upon a latching lever 220 fulcrumed on the frame of the machine at 221 (Figs. 2 and 6) and urged toward latching position by a pull spring 222 (Fig. 2) connecting its lower arm with the machine frame, the construction and arrangement being such that when the clutch member 213 is thrown into driving engagement it is so held by the lever 220 and the 55 latching arm 219 until the said latching lever

220 is turned about its pivot to unlatching position.

For so turning the lever 220 by hand, a push rod 223 (Fig. 2) is slidably mounted in the machine frame in position to be thrust against the lower arm 220^a of the lever 220 and is provided at the front end of the machine with a hand knob 224 backed by a compression spring 225 seated against the machine frame to hold the push rod 223 normally out of contact with the latching lever 220.

70 For turning the latching lever 220 to unlatching position to stop the machine automatically at the end of each operation of the winders, the upper arm 220^b of the said lever 80 extends into the path of a dog or cam 226 mounted on the periphery of the cam disk 174.

75 To prevent over-running of the machine upon the disengaging of the clutch member 213 a brake arm 227 (Fig. 6) is secured upon the shaft 216 and is adapted to coact with the braking surface 33^b formed upon the clutch member 33^a under the force of the spring 218 when the clutch is disengaged.

85 For throwing the clutch into engagement, the front end of the shaft 216 has secured thereon an arm 228 (Figs. 1, 2 and 7) which has its lower end pivoted at 229, with substantial play, to a downwardly extending 90 arm 230, operating past an over-center position (Fig. 1), of a bell crank lever 231 fulcrumed upon a stub shaft 232, the other arm 233 of the bell crank lever being connected by 95 a link 234 with a foot lever 235 fulcrumed at 236 on a bracket rising from the base of the machine, an intermediate part of the link 234 being connected by a pull spring 237 with a higher part of the machine frame, so that the spring 237 acts with the spring 218 to 100 urge the clutch member 213 toward de-clutched position. Thus the arrangement is such that depressing the foot lever 235 engages the clutch and the clutch thereupon is held engaged by the latching lever 220 and the latching arm 219 of the lever 215 (Fig. 6) until the lever 220 is tripped, either by the operator pressing the hand knob 224 or by the cam or dog 226 striking the upper arm 220^b of the lever and forcing it to the position indicated in broken lines in Fig. 3.

105 Secured to the machine frame in position automatically to receive upon it the successive bead cores ejected from the winders is a large hook 238 (Fig. 7).

110 The multiple-bearing bracket 11 preferably is mounted upon a slide 11^a provided with a handwheel 11^b (Fig. 1) and feed screw 11^c (Fig. 2), and the rotating parts adjacent the bracket are swiveled thereto, and splined upon the transverse shafts of the machine as shown at 300, 300 and 301, 301 in Fig. 1, so that the left-hand winder 13 and its associated mechanisms can be all adjusted together from and toward the other winder, as 115 120 125 130

indicated by the dotted line position of the tape-drawing slide in Fig. 1, to adapt the machine for bead-cores having the ends of the winding overlapped a greater or less distance.

Operation

In the operation of the machine, the motor and connected parts up to and including the 10 clutch member 33^a being continuously driven but with the clutch disengaged, the core-drawing slides 43, 44, 47^a, 48 being in their forward positions, the tape-drawing slides 97, 98 being in their upper positions and the 15 toggle actuating arms 203, 204 being in their upper positions with the studs 207 and 208 stopped in their notches, the operator presents a bead core 39 to the core-drawing devices as shown in broken lines in Fig. 2 and 20 passes the core into the notches of the pivoted plates, such as the notch 60 there shown, and further lifts the core, which turns the plates upward to their work confining positions, in 25 which they are latched by coaction of the stud such as the stud 64 with the spring clip 58. such as the spring clip 68.

The operator then depresses the foot lever 235, which throws in the clutch, the lever 220 automatically latching it in driving engagement.

In the resulting operation of the machine, the descent of the toggle actuating levers 203, 204 spreads apart the tape-gripping and severing slides, such as the slides 185, 187, to the 35 positions shown in Fig. 4, after which descent of the tape-drawing slides 97, 98 carries the end portions of the tapes past the axis of the winders, as shown in Fig. 4, in position to receive the bead core 39 upon the arrival 40 of the latter, the presser rollers 141, 143 being held in retracted position at this time by the cam arm 169.

The core manipulating slides are then 45 drawn rearwardly, pulling the bead core through the radial slots of the winders to the wrapping position at the axis of the winders, and upon the arrival of the bead core against or adjacent the tape ends, the arm 50 169 is lowered from the position of Fig. 4 to the position of Fig. 3, permitting the spring 157 to force the rollers 141, 143 against the end portion of the tape and stick the latter to the bead core by rolling in opposite 55 directions thereon to the position shown in Fig. 3. The tape-drawing slides then rise, sliding upward on the tapes, whose lower ends are now anchored to the bead core, and as soon as the tape-drawing slides have risen 60 from between the gripper and cutter slides 185, 187 the latter are brought together upon the tape by a rising movement of the arm 203 to its original position, the shear blades 195, 197 severing a suitable length from the tape as 65 the slides come together, and the gripper

members 199, 201 of the slides gripping the severed length of tape.

Immediately thereafter, the mutilated gear 30 comes into mesh with the pinion 29 (see Fig. 5), the cam 181 lifts the pawl 177, and the winders are consequently rotated, through a sufficient number of revolutions to completely wind the severed lengths of tape upon the bead core, the winders then stopping when the mutilated gear 30 passes out of mesh with the pinion 29 and the pawl 177 drops into the notch 176 (see Fig. 5) of the ratchet disk 175, the winders stopping with their radial slots in registry with the slots of their shafts.

Continued rotation of the main drive shaft then causes the core manipulating slides 43, 44, 47^a, 48 to run forward until their working engaging portions are beyond the peripheries of the winders, to the positions shown in broken lines as to the slide 48 in Fig. 2, and as the pivoted core-retaining plates, such as the plate 58, pass the peripheries of the winders they are forced downward about their pivots by engagement with the respective pawl-like trippers such as the one shown at 70, releasing the wrapped bead core and permitting it to drop into a position in which it is pendently supported by the hook 238 (Fig. 7).

The dog 226 on the cam disk 174 then engages the upper arm 220^b of the latching lever 220 and disengages it from the latching arm 219 of the lever 215 (see Fig. 6), which permits the springs 218 (Fig. 6) and 237 (Fig. 7) to throw out the clutch and apply the brake 227 (Fig. 6), and thereby stop the machine.

The operation as described is then repeated as to successive bead cores.

Various modifications are possible within the scope of my invention as defined in the appended claims.

I claim:

1. A wrapping machine comprising means for supporting an article to be wrapped, means for feeding to the wrapping position the leading end portion of a strip of wrapping material, and means having an orbital movement about the article for winding the strip about the article.

2. A wrapping machine as defined in claim 1 in which a plurality of strip feeding and winding means are interconnectedly mounted to operate simultaneously upon the article at longitudinally spaced-apart positions thereon and to be adjusted, together with the strip-feeding means, from and toward each other.

3. A wrapping machine comprising means for supporting an article to be wrapped, means for severing a length from a strip of wrapping material, means having an orbital movement about the article for winding the severed length about the article and auto-

matic means for removing the wrapped article from the wrapping machine.

4. A wrapping machine comprising means for supporting an article to be wrapped, 5 means for feeding to the wrapping position the leading end portion of a strip of wrapping material, means for severing a length from the said strip, and means having an orbital movement about the article for winding 10 the severed length about the article.

5. A wrapping machine comprising an open ring type winder, abutment means approximately at the axis of the said winder and means for drawing an article into the 15 winder from a direction transverse to the latter's axis and for clamping it in winding position.

6. A wrapping machine comprising a plurality of ring-type winders spaced apart 20 longitudinally of the work, abutment means approximately at the axis of each of the winders, and means for clamping an article in winding position against said abutment means, the said abutment means and the said 25 clamping means, axially of the winders, being positioned closely adjacent the winders.

7. A wrapping machine comprising a ring type winder, means for clamping an article in winding position in the winder by 30 fixed engagement with the article closely adjacent the winder, means for feeding to the winding position the leading end portion of a strip of wrapping material, means mounted at a determinate distance from the 35 winding position for severing a length from the said strip, and means for attaching the leading end portion of the said length to the article.

8. A wrapping machine comprising a 40 winder, means for holding an article in winding position in the winder, means for feeding to winding position the leading end portion of a strip of wrapping material, and means for attaching the said strip to 45 the article.

9. A wrapping machine comprising an open ring type winder, means for drawing an article into the winder from a direction transverse to the winder's axis, and means 50 for ejecting the article from the winder.

10. A winder comprising a winder ring, means mounted on the winder ring for attaching the leading end portion of a strip of material to an article mounted in said 55 ring, means for driving the winder ring, and means operatively connected with the said driving means for actuating the said attaching means by movement of the latter from and toward the article.

60 11. A winder as defined in claim 10 in which the attaching means comprises a yieldingly impelled roller adapted to run upon the winding of material lengthwise of the material as the latter feeds from the 65 winder ring onto the article and to press it

against the article in the winding operation.

12. A winder comprising a rotatable winder ring, a pair of strip-grippers mounted thereon, and means non-rotatable with the winder ring for effecting relative movement of the said grippers from and toward each other. 70

13. A winder comprising a rotatable winder ring, a strip-cutter mounted thereon, and means non-rotatable with the winder 75 ring for actuating the said cutter.

14. A winder comprising a rotatable winder ring, a work-pressing member mounted thereon, and means non-rotatable with the winder ring for actuating said 80 work-pressing member.

15. A winder comprising a rotatable winder ring, a work-pressing member and a pair of strip-grippers mounted thereon, and means non-rotatable with the winder 85 ring for actuating the said work-pressing member and the said strip-grippers.

16. A winder comprising a winder ring, a work-manipulating device mounted thereon, and means non-rotatable with the winder 90 ring for actuating the said device, and means for driving and automatically stopping said winder ring, the said means for actuating the work-manipulating device being so mounted that a part of the said device will be in engagement therewith when the winder ring is stopped. 95

17. A wrapping machine comprising means for supporting an article to be wrapped, means including a member movable toward the article for feeding to the wrapping position the leading end portion of a strip of wrapping material, and means having an orbital movement about the article for winding the strip about the article. 100 105

In witness whereof I have hereunto set my hand this 15th day of April, 1927.

FRANK SLUSHER.

CERTIFICATE OF CORRECTION.

Patent No. 1,837,840.

December 22, 1931.

FRANK SLUSER.

It is hereby certified that error appears in the printed specification of the above numbered patent requiring correction as follows: Page 6, line 17, claim 5, after "position" insert the words "against said abutment means"; and that the said Letters Patent should be read with this correction therein that the same may conform to the record of the case in the Patent Office.

Signed and sealed this 24th day of January, A. D. 1933.

(Seal)

M. J. Moore,
Acting Commissioner of Patents.
